Primary Examiner — T Chase Nelson*Assistant Examiner* — Jamillah Khalil Abdullah(74) Attorney, Agent, or Firm — IP Attorneys Group, LLC(57) CLAIM

The ornamental design for an upper for a shoe, as shown and described.

DESCRIPTION

FIG. 1 is a perspective view of an upper for a shoe in accordance with my new design;

FIG. 2 is a top view thereof;

FIG. 3 is a left side view thereof;

FIG. 4 is a right side view thereof;

FIG. 5 is a back view thereof; and,

FIG. 6 is a front view thereof.

The broken lines show environmental structure as well as portions of the upper for a shoe that form no part of the claimed design.

1 Claim, 5 Drawing Sheets(56)
